FIG. 1 is a perspective view, showing my new design and illustrating the cable way of the present invention as it would appear mounted to a wall surface, the phantom line portions forming no part of the design;

FIG. 2 is a rear quartering perspective view of the cable way illustrated in FIG. 1, the phantom line portions forming no part of the present invention;

FIG. 3 is a cross-sectional view of the cable way illustrated in FIGS. 1 and 2; and,

FIG. 4 is an exploded view taken generally in the area depicted at 4 in FIG. 3.
